MAGAZINE ROCKET PROJECTORS

Johannes Linke and Hans Michel, Zurich, Switzerland, assignors to Machine Tool Works Oerlikon, Administration Company, Zurich-Oerlikon, Switzerland, a Swiss company

Application June 17, 1957, Serial No. 665,934

Claims priority, application Switzerland July 4, 1956

1 Claim. (Cl. 89—1.7)

The invention relates to a rocket projector having a magazine containing the rockets, a loading chamber with adjoining firing tube, and means for the automatic feeding of the rockets from the magazine into the loading chamber.

In the rocket projectors of this kind as hitherto known when firing a series of rockets the same are moved during the intervals between firing jerkily by follow-up means towards and into the firing position. At the beginning of the follow-up movement accordingly all the rockets in the magazine have to be accelerated from rest, and at the end of the same they have to be braked again. For a rapid sequence of shots, i.e. at a high cadence of the weapon, because of the comparatively large masses to be moved, very strongly dimensioned drives for the follow-up means and often also special devices such as clutches, brakes and the like are required. The drive and follow-up means thereby become heavy and occupy a correspondingly large space.

It is an object of the present invention to provide a rocket projector wherein these disadvantages are overcome, and wherein in particular no high inertia forces occur and the conveyor device does not require a high power input and may be of lighter construction.

With this and other objects in view I provide a rocket projector comprising in combination: a magazine adapted to contain the rockets, a loading chamber having an adjoining firing tube, a feeder drum uniformly rotated when firing a series of rockets and moving the said rockets from the said magazine into the said loading chamber, a spring-loaded closure flap operated by the rockets entering into the said loading chamber and cooperating with special closure faces provided on the said feeder drum in shutting off the said loading chamber during the firing, a carrier shiftably mounted in the said magazine behind the last rocket contained therein, belt drums in driving connection with the said feeder drum, and tension belts adapted to be wound on and off the said belt drums and attached to the said carrier, imparting to the latter the feed required for conveying the rockets into the said feeder drum.

A free-wheel coupling may be interposed advantageously in the said driving connection from the said feeder drum to the said belt drums.

These and other objects and features of our said invention will be clearly understood from the following description of an embodiment thereof given by way of example with reference to the accompanying drawings, in which:

Fig. 1 is a cross section along line I—I of Fig. 3 of a rocket projector with the magazine partly filled,

Fig. 2 is a part cross section on the line II—II of Fig. 3,

Fig. 3 is a longitudinal section of the feeder drum on the line III—III of Fig. 1,

Fig. 4 is a longitudinal section of a belt drum on the line IV—IV of Fig. 1,

Fig. 5 is a section on the line V—V of Fig. 3,

2

Fig. 6 is a section of a belt drum on the line VI—VI of Fig. 3,

Fig. 7 is a section on the line VII—VII of Fig. 6,

Figs. 8—11 are diagrammatic illustrations of various phases of the rocket feed and of the loading operation, Fig. 9 corresponding to the moment of initiating the starting of a rocket,

Figs. 12—15 are diagrammatic illustrations of various phases of the re-loading operation, Fig. 15 representing the moment of insertion of a rocket into the feeder drum.

The rocket projector according to Fig. 1 consists substantially of a magazine 1, a casing 2 with a feeder drum 3, a loading chamber 4 and a starting tube 5 which is only diagrammatically indicated in Fig. 3. A tubular carrier 6 of the same diameter and length as the rockets 7 is in driving connection with the feeder drum 3 through belts 11 passing over deflector wheels 8 and deflector rollers 9 and 10, and supplies the said drum with rockets. The feeder drum is in its length subdivided into individual sections, which are connected with one another by short tubular pieces 13 attached perpendicularly to walls 12 (Fig. 3). These sections are formed each by two equal tubular segments 14 arranged symmetrically with respect to their longitudinal axis, and by the walls 12 fixed perpendicularly at their ends. The exterior surfaces of the tubular segments 14 (see Fig. 2) will be referred to hereinafter as closure surfaces 15, and the narrow surfaces of the side walls 20 and of the partition walls 12 (see Figures 3 and 2), parallel to the longitudinal axis of the feeder drum, will be referred to as control surfaces 17 and 18. These control faces of the individual walls 12 and 20 are formed symmetrically with respect to the longitudinal axis of the feeder drum. A control face is formed by two portions, namely a circular recess 17 (Fig. 1), the radius of which is slightly larger than the radius of the rocket bodies, and a circular portion 18 of opposite curvature tangentially adjoining 17. coaxially to the longitudinal axis of the feeder drum spring loaded bolts 22 are slidably fitted into bores of discs 21 fixedly connected to the end-walls 20 (Fig. 3). These bolts serve for journaling the feeder drum in corresponding bores of driving discs 23 and 24 which are rotatably journalled in the casing; the driving disc 23 fixedly mounted on the shaft of a spur gear 25 is in driving connection with an electric motor 29 through this spur gear, an intermediate gear 26 and reduction gearing 28. Parallel ledges 30 (Fig. 5) projecting from the driving discs 23 and 24 engage with the discs 21 having parallel milled faces. The feeder drum may accordingly be driven either from the motor 29 (Fig. 3) or through a hand crank 33 adapted to be mounted on the shaft 32.

Belt drums 35 (Fig. 3), on which the belts 11 are wound, are rotatably mounted on the cylindrical connecting pieces between the discs 21 and the end-walls 20 of the feeder drum. Only when the feeder drum is turned in the direction required for the firing, the pins 36 resiliently mounted in the end-walls 20 serve for carrying along the band drums 35 in that they abut semi-circular faces 37 (Figs. 6, 7) of the latter. With the feeder drum rotating in the opposite sense the ends of the pins cannot drive the belt drums; they run up ramps 38 to the highest points 39 thereof, from where they are pushed back by the springs 41 to the bottom of the ramps.

In the upper part of the casing 2 (Figs. 2, 3) a flap subdivided into various sections 45a to 45c is pivotally mounted on axles 44 parallel to the longitudinal axis of the feeder drum 3. The flap sections 45a, 45b, 45c consist of lids 46 (Fig. 2) with substantially circular arc shaped closure faces 47 adapted to the shape of the rocket bodies. The lids which extend over the full length of the sections, are subjected to the bias of springs 48, and

are connected by ribs 49, 50 and plates 51 to hubs 52. An additional rib 53 (Fig. 2) arranged at the end of the rearmost flap section 45c restrains the rockets 7 during their feeder movement into the loading chamber 4, by engaging into annular grooves 55 (Fig. 4) in the rocket bodies from being shifted in their longitudinal direction. The same purpose is served by ribs 58 and 61 (Fig. 2) of sprung levers 56 and 59, which are rotatable about axles 57 (Fig. 3) and 60, respectively, as well as by U-profile rails 62 in the magazine (Fig. 4).

The interstices formed between the walls 12 of the feeder drum 3 are engaged by ribs 64 attached to the casing (Fig. 3), on which also slider and guide tracks 65 (Fig. 1) for the rockets are arranged. The guide tracks as well as tracks 66 connected to the casing cover together form a duct 67 through which the rockets are further conveyed to the loading chamber 4 after having emerged from the magazine 1. The center line of the conveyer duct 67 runs originally in the same direction at which the rockets emerge from the magazine, and subsequently in a direction inclined to the first one at an acute angle.

The axis of the loading chamber 4 which is designed for receiving the rockets before the firing, is determined by the centers of the portions of semi-circular cross section. The loading chamber 4, which extends over the full length of the casing, is co-axially adjoined forwardly by the starter tube 5 (Fig. 3), and rearwardly by a port 68 (Fig. 5) in the casing wall 72, through which the combustion gases of the rocket emerge. In the rear portion of the loading chamber 4 two contact pieces 70 (Fig. 1) for the electric priming of the rockets are arranged, which are connected to a source of priming current (not shown). In Fig. 1 one only of the two contact pieces 70 is visible, since the second one lies behind the visible one in the direction of the rocket axis.

The deflector rollers 9 and 10 (Fig. 1) for the belts are rotatably journaled on the casing walls 71 and 72.

The manner of operation of the feeder mechanism for the rockets follows from the structure described, and from Figs. 8-11:

The rockets (Fig. 1) are pushed by the carrier 6 out of the magazine into the duct 67 with a speed depending on the rotational speed of the feeder drum. There the actually foremost rocket is forced by a spring loaded bolt 73 and by a lever 59 into a recess 17 of the feeder drum 3, is accelerated by the latter and is guided further through the feeder duct 67 at a speed exceeding that of the subsequent rockets. Thereby it leaves the same behind, whereafter the feeder drum turns into the gap thus formed and conveys the rocket completely into the loading chamber 4.

The flaps 45a, 45b, 45c protruding into the feeder duct 67 are pushed out of their rest position by the rocket directed towards the loading chamber. As soon as the rocket lies completely in the loading chamber it is automatically primed in that its two contact points come into contact with the contact pieces 70 arranged in the loading chamber. At the same time the flaps 45a, b, c swing by the action of the springs 48 again into the feeder duct, their closure faces 47 hugging the rocket. A rocket is half encircled by the loading chamber 4 during starting and is guided along further generatrices by the closure faces 15 and 47 of the feeder drum 3 and flaps 45a, b, c.

During this period the loading chamber is closed by the closure faces 15 and 47 of the uniformly rotating feeder drum 3 and of the flaps 45, respectively (conf. Fig. 9). The combustion gases consequently can emerge practically only through the casing wall 72.

The feeder drum 3 continuing its rotation and the rocket conveyed by it re-open the loading chamber whereby the path into the same is cleared for the said rocket. The rotational speed of the feeder drum is conveniently so selected that the loading chamber is oper-

ated by the closure faces only after the started rocket has left the starting tube. After the last rocket has been conveyed into the loading chamber, a switch (not shown) is operated by the carrier 6 having reached its end position illustrated in Fig. 12, whereby the drive of the feeder drum is switched off.

The re-loading of the magazine (Figs. 12-15) is effected by pushing the rockets into the recesses 17 of the feeder drum 3 through the aperture 74 of the casing wall 72, and by turning the feeder drum by the aid of the hand crank 33 in the rotational sense opposite to the feeder movement when firing. The rockets can be inserted, when the feeder drum is in a position as illustrated in Fig. 15, into which the feeder drum has to be turned back prior to the beginning of the re-loading. When turning back, firstly the portions 18 of the control faces of the feeder drum come into contact with the tubular carrier 6, and force the same towards the magazine. Thereby so much of the belt 11 is unwound from the drum 35 that the latter does not turn relative to the feeder drum 3. When the closure face 15 thereof is in contact with the carrier 6, the latter and with it also the belt drum 35 come to a standstill, so that the feeder drum keeps turning alone and precedes the belt drum. After the first rocket has been pushed in, the carrier 6 is pushed back by the said rocket when the feeder drum is turned further back, so much of the belt being wound off the drum that its rotational path exceeds that of the feeder drum. In a position of the feeder drum as shown in Fig. 12 the belt drum has caught up with the feeder drum again, and the pins abut again the faces 35. When further re-loading the magazine, these operations are repeated.

While we have described herein and illustrated in the accompanying drawings what may be considered a typical and particularly advantageous embodiment of our said invention we wish it to be understood that we do not limit ourselves to the particular details and dimensions described and illustrated, for obvious modifications will occur to a person skilled in the art.

What we claim as our invention and desire to secure by Letters Patent, is:

In a rocket launcher the combination comprising a loading chamber having an adjoining firing tube, a projectile magazine, a conveyer duct connecting said magazine with said loading chamber, a feeder drum having control faces and closing faces entering said conveyer duct and moving the projectiles from said magazine into said loading chamber, a spring loaded closure flap operated by a projectile entering said loading chamber and cooperating with said closing faces on said feeder drum to form a closed firing chamber during firing, a carrier movably mounted in said magazine behind the last projectile contained therein, belt drums mounted coaxially and in driving connection with said feeder drum and comprising a free-wheel coupling interposed in said driving connection from said feeder drum to said belt drums, tension belts adapted to be wound on and off said belt drums and attached to said carrier, imparting to the latter the feed required for conveying the projectiles into said feeder drum and a prime-mover in driving connection with said feeder drum imparting to the latter a uniform rotation during the firing cycle.
